UNITED STATES PATENT OFFICE.

JOHN PALUCH AND JOHN PAFLITZKO, OF GARFIELD, NEW JERSEY.

STATION-INDICATOR FOR CARS.

1,147,970.

Specification of Letters Patent. Patented July 27, 1915.

Application filed January 29, 1915. Serial No. 5,062.

To all whom it may concern:

Be it known that we, JOHN PALUCH and JOHN PAFLITZKO, subjects of the Emperor of Austria-Hungary, residing at Garfield, in the county of Bergen and State of New Jersey, have invented certain new and useful Improvements in Station-Indicators for Cars, of which the following is a specification.

10 This invention relates to certain new and useful improvements in station indicators for cars.

15 The primary object of this invention is to provide a viewable means within a railway car whereby the passengers are kept advised as to the name of the next station to be reached upon the route.

20 A further object is to provide a shiftable station indicating curtain within a car adapted to be successively shifted automatically at each station along the route by a special form of trip device having an automatic means for returning the same to its normal inoperative position.

25 A still further object of the invention is to provide in connection with a station indicator for cars, an actuating means for the curtain operated by a stationary trip positioned adjacent the track upon which the car 30 is traveling and including a vertically movable claw member depressible by the trip and arranged for automatic return to its normal position by means of spring members.

35 With these general objects in view and others that will appear as the nature of the invention is better understood, the same consists in the novel combination and arrangement of parts hereinafter more fully described, illustrated in the accompanying 40 drawings and pointed out in the appended claims.

45 In the drawings forming a part of this application and in which like-designating characters refer to corresponding parts throughout the several views, Figure 1 is a front elevation of the device detached from the car and shown in partial vertical section, with the elements in their normal position and about to be actuated by the trip mechanism. Fig. 2 is a horizontal transverse sectional view thereof. Fig. 3 is a vertical sectional enlarged detail view upon the plane of the claw mounting rod. Fig. 4 is a view similar to Fig. 1 and having a side 50 portion of the front casing in position, but illustrating the mechanism in its tripping 55

position. Fig. 5 is a vertical sectional view taken upon line V—V of Fig. 1. Fig. 6 is a similar sectional view upon line VI—VI of Fig. 4. Fig. 7 is a detail front elevation of 60 a portion of the curtain mounting mechanism adjacent the brake end thereof. Fig. 8 is an end elevation of the brake mechanism, and Fig. 9 is an end elevation of the curtain 65 mounting means.

Referring more in detail to the drawings it will be noted that a casing 10 is provided which is adapted to be secured at any convenient point within a railway car, such casing being adapted to contain the indicating 70 mechanism which includes an endless curtain 11 upon which the names of the successive stations along the route are inscribed, while such names are viewable through a transparent window 12 in one side of the casing. 75 The said curtain 11 is mounted upon opposite sprocket wheels 13 carried by a shaft 14 which is journaled in opposite brackets 15 and 16 mounted within the casing. It will thus be evident that any desired name 80 which is found upon the curtain may be brought into registry with the window 12 by turning the shaft 14 in any manner such as manually by means of the end wheel 17 to which access may be had by means of the 85 hinged door 18 of the said casing.

A base 19 is provided in the casing 10 upon which are mounted spaced posts 20 having vertical longitudinal slots 21 therethrough and in which slots a mounted rod 22 90 is slidably positioned. A hook or claw 23 is journaled upon the rod 22 between two collars 24 which are fixed to the said rod, while the free end of the rod has its hook 25 normally engaging the uppermost positioned rod tooth 26 of the wheel 27 fixed to the said curtain shaft 14, and as best illustrated in Figs. 1 and 5 of the drawings. Expansion springs 28 are positioned between the base 19 and the rod 22, the said 100 springs having their outer ends attached to collars 29 journaled upon the said rod adjacent the opposite ends thereof and between the pairs of spaced collars 30. A similar expansion spring 31 is positioned between the base 19 and the lower end of the claw 23 so that the expanding tendency of all of said springs 28 and 31 is to normally 105 position the rod 22 at the upper limit of its movement and with the claw hook 25 engaging the said top tooth as shown in Fig. 5, which engagement is further assisted by

means of a contraction spring 32 connecting the claw 23 with the adjacent side of the casing 10.

A stationary trip bar 33 is positioned adjacent the track at each railway station being secured to any permanent support such as the post 34. A trip rod 35 projects through the side of the casing 10 and is journaled in a bracket 36 carried by the base 19, the said trip rod being capable of rotating as well as having a slight longitudinal movement, but being normally held in the position shown in Fig. 1, by means of an encircling helical spring 37 which latter is engaged between the mounting bracket 36 and a cross arm 38 of the said trip rod. The said trip rod arm 38 is normally positioned vertical and is arranged adjacent the claw mounting rod 22 so that when the trip bar 33 is engaged by the trip rod 35 so as to impart a partial revolution to the said trip rod, the adjacent end of the arm 38 engages the upper side of the rod 22 and imparts a downward sliding movement to the said rod as best illustrated in Fig. 6, and which movement pulls downwardly the claw hook 23 thus moving the wheel 27 substantially a quarter turn and bringing a succeeding portion of the curtain directly behind the window 12 and upon which curtain portion the name of the next succeeding station along the route is inscribed.

The rod 14 is provided upon the end thereof adjacent the bracket 16 with a brake device as best illustrated in Fig. 8 and consists of a star wheel 39 fixed to the shaft and provided with a brake shoe 40 resiliently positioned against the said star wheel by means of a contraction spring 41 which engages the angular arm 42 of the said brake-shoe, the said arm being pivoted as at 43 to a mounting bracket 44 carried by the casing.

From this detailed description of the invention, the complete operation thereof will be at once apparent. With the mechanism normally positioned as shown in Fig. 1, the car having the casing 10 thereon will engage the angular outer end 45 of the trip rod with the station bar 33 and the trip mechanism operating in the manner hereinbefore set forth, the name of the next succeeding station along the route will be plainly visible through the casing window 12 and such name will remain in full view of the passengers upon the car until the next station is reached whereupon the curtain will be automatically shifted in a similar manner for displaying the name of the next station.

The brake mechanism shown in Fig. 8 is adapted only to act as a slight retaining means for the curtain mechanism when positioned by the trip device in its step-by-step movement, it being understood that the rotation of the rod 14 permits the brake shoe

40 to ride over the star wheel from one engaging portion thereof to the next succeeding portion.

A device is therefore provided which accurately fulfills the objects desired for the device and one in which the curtain actuating means furnishes a positive and efficient automatic shifting mechanism.

While the form of the invention herein shown and described is what is believed to be the preferred embodiment thereof, it is nevertheless to be understood that minor changes may be made without departing from the spirit and scope of the invention as set forth in the claims.

What is claimed as new is:—

1. A device of the class described comprising a casing, a station indicating curtain mounted within said casing, a rocking trip rod projecting outwardly of the casing, a cross head upon the inner end of said rod, a claw and wheel actuating means for the said curtain, a vertically shiftable rod for the said means positioned in the path of movement of the said trip rod head, and expansion elevating return means for the said vertically shiftable rod.

2. A device of the class described comprising a station indicating curtain, an operating wheel for the said curtain, spaced posts having vertical longitudinal slots there-through, a shiftable rod mounted within said slots, a claw arm engageable with the said wheel and journaled upon the said rod, a compression spring having one end attached to the said arm and its other end fixedly mounted at a point in a vertical plane adjacent the opposite side of the said wheel, expansion means beneath the said rod and arm adapted for normally maintaining the said rod in its elevated position, and trip actuating means for the said rod.

3. A device of the class described comprising a station indicating curtain, an operating wheel for the said curtain, spaced posts having vertical longitudinal slots there-through, a shiftable rod mounted within said slots, a claw arm engageable with the said wheel and journaled upon the said rod, a compression spring having one end attached to the said arm and its other end fixedly mounted at a point in a vertical plane adjacent the opposite side of the said wheel, a base upon which said posts are mounted, collars fixed to the said rod at opposite sides of the said arm, an expansion spring positioned between the said base and the lower end of the said arm, sleeves journaled upon said rod adjacent the opposite ends thereof, expansion springs positioned between the said base and the said sleeves, and trip actuated shifting means for the said rod.

4. A device of the class described comprising a station indicating curtain, an operat-

- ing wheel for the said curtain, spaced posts having vertical longitudinal slots therethrough, a shiftable rod mounted within said slots, a claw arm engageable with the 5 said wheel, and journaled upon the said rod, a compression spring having one end attached to the said arm and its other end fixedly mounted at a point in a vertical plane adjacent the opposite side of the said 10 wheel, a base upon which said posts are mounted, collars fixed to the said rod at opposite sides of the said arm, an expansion spring positioned between the said base and the lower end of the said arm, sleeves journaled upon said rod adjacent the opposite ends thereof, expansion springs positioned between the said base and the said sleeves, a rocking rod having an angular outer extension, a fixed trip bar positioned in a line of 15 20 25 travel of the said extension as normally positioned and a cross arm carried by the inner end of the said rocking rod having a path of travel transversely of the normal position of the said shiftable rod.
5. An actuating means comprising spaced 25 posts having longitudinal slots therethrough, a shiftable rod positioned through the said slots, an actuating claw journaled upon said rod, normal positioning resilient elevating means beneath the said rod, a bracket, a 30 rocking rod journaled and slidable within the said bracket and having an outer angular extension, a cross head upon the inner end of the said rocking rod having a path of travel transversely of the normal position 35 of the said shiftable rod.

In testimony whereof we affix our signatures in presence of two witnesses.

JOHN PALUCH.
JOHN PAFLITZKO.
